R. VINCENT.

Plow.

No. 22,389.

Patented Dec. 21, 1858.

UNITED STATES PATENT OFFICE.

REED VINCENT, OF ROCKTON, ILLINOIS.

IMPROVEMENT IN PLOWS.

Specification forming part of Letters Patent No. 22,389, dated December 21, 1858.

To all whom it may concern:

Be it known that I, REED VINCENT, of Rockton, in the county of Winnebago and State of Illinois, have invented a new and useful Improvement on Plows; and I do hereby declare that the following is a clear, full, and exact description of the construction and operation of the same, reference being had to the annexed drawings, making a part of this specification, in which—

Figure 1 is a perspective view, and Fig. 2 a vertical section through the red line xx of Fig. 1; letter A being a convex standard; letter B being a perpendicular brace; letter C being a curved handle, secured by a bolt to perpendicular brace B; letter D being a horizontal brace extending from convex standard A to perpendicular brace B, connecting and supporting the same; letter E being a bolt securing the standard to the side of the beam; letter F being a bolt securing perpendicular brace B and horizontal brace D combined to the under

side of the beam; the convexity of the standard A and the curved handle C connected by a bolt with perpendicular brace B, accomplishing in its operation the effect of clearing perfectly and preventing all clogging by grass, stubble, or straw, and the combination of the braces, and the connection of the same with the standard securing a greater amount of strength and durability than any other pattern hitherto invented.

What I claim as my invention, and desire to secure by Letters Patent, is as follows:

The combination of the convex standard A, the braces B D, and the mold-board, when arranged in connection with the beam and bent handles C as described and represented, and for the purpose set forth.

REED VINCENT.
